U.S. Appl. No. 29/394,324, filed Jun. 15, 2011; Inventor: Brian James Kelleghan.

* cited by examiner

Primary Examiner — Ralf Seifert(74) *Attorney, Agent, or Firm* — Abigail Smith; Oppedahl Patent Law Firm LLC(57) **CLAIM**

The ornamental design for an attachment device, as shown and described.

DESCRIPTION

FIG. 1 is a top perspective view of an attachment device showing my new design.

FIG. 2 is a right side perspective view;

FIG. 3 is a top plan view;

FIG. 4 is a bottom plan view;

FIG. 5 is a left side elevation view;

FIG. 6 is a right side elevation view;

FIG. 7 is a front side elevation view; and,

FIG. 8 is a rear side elevation view.

The broken line showing of a continued length of the item attached to the attachment device is shown for illustrative purposes only and forms no part of the claimed design.
